UNITED STATES PATENT OFFICE

BENJAMIN S. MAHAFFEY, OF CHICAGO, ILLINOIS

DISPLAY AND DISPENSING APPARATUS

Application filed November 17, 1925. Serial No. 69,640.

This invention relates to a display and dispensing apparatus for nuts and other food products, and particularly an apparatus which is adapted for displaying peanuts or 5 other nuts, or bags containing same for retail sale in stores.

The object of the invention is to provide a novel and simple display apparatus including containers of suitable vitreous material 10 which is transparent, such as glass or other suitable material which will protect the nuts or the like against deterioration and which will also prevent access thereto by rodents, such as mice, which has heretofore presented 15 a very serious difficulty in keeping such products, especially nuts, on hand and display for retail sale or otherwise. The invention embodies a novel means for readily dispensing the goods in question and for making provision 20 to support the same upon a rotatable or other counter display device, such as a revolving display stand for selling salted nuts.

With the above and other objects in view, the invention consists of certain novel combinations and arrangements of parts to be 25 hereinafter more fully specified and pointed out particularly in the claims.

In the accompanying drawings:

Fig. 1 is an elevation of a revolving display stand having a novel display and dispensing device associated therewith.

Fig. 2 is a plan view of the device.

Fig. 3 is a fragmentary central vertical sectional view of the display stand.

Fig. 4 is an enlarged sectional view of the display stand taken on the line 4—4 of Fig. 1, and

Fig. 5 is an enlarged sectional view of one of the vitreous or glass containers and showing the mounting thereof on a removable slide 40 or plate.

Referring to the drawings in detail, in which like reference characters designate corresponding parts throughout the several 45 views, the display and dispensing apparatus is shown as embodying or associated with a revolving display stand including a base 6, of wood or the like over which a cover section 7, of sheet metal or the like and may be 50 secured as indicated at 8 along the surround-

ing edges of the base. The base may be provided with a central vertical projection 9, adapted to take a pivot bolt 10, having a nut 11, secured on the lower end thereof and embedded in a recess 12, of the base, to permit 55 the base to set flat on a showcase or other support while retaining the bolt in position. The bolt has a tapered head 13, at its upper end upon which a bearing arm or bracket 14, engages in the recessed bottom base there- 60 of as clearly shown in Figure 3 of the drawings. This bracket is secured as at 15, to a bottom member 16, such as wood, having a central aperture 17, through which the bolt end is extended to retain the revolving part 65 of the stand in position, but permit it to revolve on the bearing as it is thought will be obvious.

The stand in addition to the bottom portion 16, includes a shell of rectangular or other cross section forming an upright stand or body member 18, which may be composed of a series of side plates 19, attached to the members 16, and a top member 20, over which a sheet metal or other top portion 21, is secured as indicated at 22. The vertical side edges of the plates 19, are bent in opposite directions toward each other to form guides 23, opposing each other at opposite vertical side edges of the plate or respective sides of 70 the stand, and these may be enveloped by corner sections 24, of angular formation having their edges turned in around the oppositely directed portions 23, as indicated at 25, to cover the exposed rough or raw edges of 75 the metal to prevent injury to the hands and also serve to frictionally retain removable cards or display plates 26, preferably of sheet metal, therebeneath. These plates are adapted to be slid in at the top edges of the 80 sides beneath such guideways to detachably mount the same on the stand proper and are supported at their lower ends or bottom edges by stops 27, formed in a suitable manner and by turning in the lower ends of the angular 85 corner strips 24, or by suitable lugs or stops formed on the lower ends of the side plates 19.

In order to mount the packages of food or delicacies, such as salted nuts which may be in bags, usually five or ten cent packages 90

to be disposed as in retail trade, as indicated at 28, suitable vitreous and transparent containers 29, such as glass, or the like are provided. These containers may be suitably 5 mounted upon the plates or sides 19, of the display stand or preferably mounted on the cards or removable side plates 26, which are detachably mounted in the guides and the containers are detachably mounted on the 10 slides or plates 26, so as to be readily removed for removing the contents thereof for sale. As shown in the drawing, screw caps or other suitable caps provided for the containers 29, and designated in 30, are mounted 15 upon the slides of plates 26, and secured thereto in any desired way as by soldering or welding as indicated at 31, and the containers may have threaded connection with the attaching means or caps 30, as indicated 20 at 32. The cap and container may have an interposed paraffin disk or the like 33, to protect the contents by effectively closing the connection or joint. The containers and mounting means therefor may be arranged 25 in any suitable relations on the slides or plates 26, and as shown in Figures 1 and 2, of the drawing are preferably arranged in staggered spaced relation to provide an attractive display of the dispensing apparatus and also to increase the holding capacity of the device.

In view of the foregoing, it is evident that I have provided a very efficient and easily manipulated display and dispensing apparatus which is especially adapted for dispensing nuts or other foods products, and particularly the former, which will entirely protect the nuts against deterioration due to exposure, but will above all, protect the food products and especially nuts from access thereto by rodents, such as rats or mice or other animals or insects that will attack the same. The customer can then be sure of purchasing the nuts in proper condition. It is also to be understood that the glass containers or small jars may be attached to the plates or supports, by other suitable holding means, by means of the caps or jars by strings, rubber bands, steel clasps or otherwise, such as hooks and eyelets, or soldered or riveted as described to the stand or display card or plate. It will also be understood that various changes may be made in the arrangement and combination of parts 45 shown and described, and that other materials may be employed without departing from the spirit and scope of the invention as will be defined by the claims. It may also be apparent that suitable transparent material or 50 containers other than glass may be employed to carry out the objects of the invention.

Having thus described my invention, what I claim is:

1. In a dispensing and display apparatus 55 of the class described, a revolving stand hav-

ing guides, slides in said guides, closure members secured to the slides and transparent containers removably held in outwardly extending positions by said closure members.

2. A device for displaying and dispensing 70 goods of the class described including a rotatable vertically disposed display plate, a screw closure cap secured to the same at its closed side and having its open portion projecting horizontally outwardly, and a glass 75 container having an externally threaded open end screwed in said cap and detachably supported thereby in a horizontal outstanding position and sealing the interior contents of the container.

3. In a dispensing and display apparatus, 80 a rotatable vertically disposed display plate, a screw closure cap secured by its closed end to said plate and having its open end projecting horizontally outward from said plate, and a glass container having an externally threaded end 85 screwed in said cap and detachably supported thereby in horizontal outstanding position.

4. In a dispensing and display apparatus, 90 a display plate, a screw closure cap secured by its closed end to said plate and having its open end projecting horizontally outward from said plate, and a glass container having an externally threaded end 95 screwed in said cap and detachably supported thereby in horizontal outstanding position.

In testimony whereof I affix my signature.

BENJAMIN S. MAHAFFEY.
